UNITED STATES PATENT OFFICE.

WILLIAM MEREDITH HOLLIDAY, OF PENRITH, NEW SOUTH WALES, AUSTRALIA,
ASSIGNOR TO ALBERT JACOB BERT, OF SYDNEY, AUSTRALIA.

COMBINED BOX AND PRESS FOR PNEUMATIC-TIRE-REPAIR OUTFITS.

1,294,464.

Specification of Letters Patent.

Patented Feb. 18, 1919.

Application filed March 14, 1916. Serial No. 84,017.

To all whom it may concern:

Be it known that I, WILLIAM MEREDITH HOLLIDAY, a subject of the King of Great Britain, residing at St. Thomas' Rectory, 5 Mulgoa Road, Penrith, in the State of New South Wales and Commonwealth of Australia, clerk in Holy Orders, have invented a new and useful Combined Box and Press for Pneumatic-Tire-Repair Outfits, of which 10 the following is a specification.

This invention has been specially devised in order to provide an improved combined box and press of compact cheap and simple construction which is especially adapted to 15 contain repair outfits for pneumatic tires and also to form an efficient press for a repaired portion of said tires such as a patched tube and thus obviating the necessity of carrying a separate press for such 20 purposes.

This improved combined box and press specially suitable for pneumatic tire repair outfits comprises a box with a lid disconnected therefrom capable of having its outer 25 face positioned parallel with the outer face of the bottom of the box adapted to be pressed thereto and secured in such position by clips or fastenings pivotally connected to said box or to said lid and comprises a 30 box with a lid connected thereto capable of being reversed upon or around its connection until its outer face positions parallel and close to the outer face of the bottom of the box and of being pressed toward said 35 bottom and being secured in such position.

In general the lid is connected to the box by a double hinge whose one center of movement is about half way between the top and the bottom of the box so that upon the lid 40 being semi-reversed around the outer center of movement the lid and outer center may be radially moved around said inner center of movement a half turn and the lid further reversed on its outer center of movement so 45 that its outer face is parallel with and close to the bottom of the box. Clips or fastenings on the box may then be positioned over the edges of said lid causing the lid to press hard upon anything between said 50 lid and the bottom of the box and to hold the lid in such position exerting pressure as long as may be desired. By preference these clips or fastenings take the form of a broad staple whose limbs are turned in or 55 out parallel with its continuous end to form

an inner hinge for said staple which takes over the outer face of the lid of the closed box on reversal of the lid and forms a brace from the inner hinge over the said reversed lid. Or the clipping or fastening may be 60 part of the function of the double hinge made with withdrawable hinge pins allowing the reversal of a hinge piece.

But in order that a practical application of the invention may be easily carried out 65 this improved box and press as preferably constructed will now be described with reference to the accompanying drawings in which Figure 1 is a perspective view of a box closed; Fig. 2 is a similar view of the 70 same open and Fig. 3 is a similar view with box reversed and the lid semi-reversed on both hinges or centers of movement while Fig. 4 is a similar view of the box with the lid completely reversed against the bottom 75 of the box and acting as a press and Fig. 5 is a transverse section of Fig. 4. Figs. 6 and 7 are similar views to Figs. 3 and 4 showing a modified construction of hinge and fastening.

The box 8 has a lid 9 hinged thereto by the connecting end 10 of a broad wire staple whose turned in limbs 12 take into the box ends near its sides and medially of its depth. The lid 9 is adapted to be locked by a staple 85 wire 13 similarly hinged to the box at the opposite side as the staple 11 at the ends medially of its depth. And this clip is adapted to lock over small projections 14 on the box when the lid is in closed position. 90

In a modified construction flat hinge pieces 16 are provided for the hinge and for the fastenings and each of these has homings 18 through which and through homings 19 stamped out of or formed upon the box 8 95 passes a pin 20 and through which homings 21 on the lid passes a pin 22 but on the hinge side the pins 20 and 22 form part of a staple though on the fastening side the pin 22 must be removable.

In the construction of box having a disconnected lid it is necessary to have staples such as 13 pivoted to the box ends or sides or to the lid ends or sides medially thereof so that the connecting ends of said staples 105 will in upper or lower position take tightly over the outer surface and the edge of the lid respectively.

In use when it is desired to use a press the lid is reversed over upon the body until its 110

outer face is opposite the bottom of said box and the material 15 say a patched tire placed between said face and said bottom when the clip 13 is then turned over and locks the 5 whole together as shown in Figs. 4 and 5 for as long as required.

The reversal of the lid in the construction shown in Figs. 6 and 7 transforms it into a 10 press similarly as before described and it is fastened by replacement of the removable pin 22.

What I claim is:

1. A combined box and press comprising 15 a lid for the box adapted both to fit the top of the latter in closed position and to be placed in reverse position beneath the box so as to coact with the bottom wall thereof, to provide coacting pressing members, between which is placed an article to be pressed, and 20 means for securing the lid to the box, said means being movable to vary the pressure between the members.

2. A combined box and press comprising 25 a lid for the box adapted both to fit the top of the latter in closed position and to be placed in reverse position beneath the box so as to coact with the bottom wall thereof, to provide coacting pressing members, between which is placed an article to be pressed, and 30 means for securing the lid to the box, said means being movable to vary the pressure between the members and to force the lid into snug engagement with the top of the box.

35 3. A combined box and press comprising a box, a lid for the box, a staple hinge pivotally connecting the lid with the box and being disposed so that the lid will snugly fit the top of the box when in closed position 40 and may be swung into reverse pressing position beneath the bottom of the box in par-

allelism therewith and in suitable proximity thereto to accommodate an article to be pressed therebetween, and a staple fastener pivoted on the box and disposed so that it is 45 adapted to span and embrace the lid and secure it in either position.

4. A combined box and press comprising a box, a lid for the box, a hinge member pivotally connecting the lid with the box and 50 being constructed and arranged so that the lid will snugly fit the top of the box when in closed position and may be swung into reverse pressing position beneath the bottom of the box in spaced relation thereto to accommodate an article to be pressed therebetween, a staple fastener pivoted on the box and disposed so that it is adapted to span the lid and secure it in either position, and 55 projections provided on the lid and situated so that the fastener will slip over the same with difficulty, thereby drawing the lid into tight engagement with the top of the box and preventing accidental displacement of the same.

5. A combined box and press comprising a box, a lid for the box having depending flanges thereon, means for securing the lid to the box to permit swinging thereof to the bottom of the box and reverse its relation 70 thereto so as to coact with the box to provide pressing members, and pivoted means carried by the box and movable to engage said flanges for forcing the lid toward the box.

In testimony whereof I have signed my name to this specification in the presence of two subscribing witnesses.

WILLIAM MEREDITH HOLLIDAY.
